UNITED STATES PATENT OFFICE.

JOSEPH RICE, OF CHICAGO, ILLINOIS.

CONTAINER AND OPENER.

1,249,497.

Specification of Letters Patent. Patented Dec. 11, 1917.

Application filed November 20, 1915. Serial No. 62,456.

To all whom it may concern:

Be it known that I, JOSEPH RICE, a citizen of the United States, residing at Chicago, in the county of Cook and State of Illinois, have invented a new and useful Improvement in Containers and Openers, of which the following is a specification.

My invention relates to containers and openers therefor, and has for its object the provision of a container adapted to hold confections and the like, which is sanitary, simple of construction and efficient in use. A further object is the provision of a simple opener for the container. Other objects will appear hereinafter.

An embodiment of my invention is shown in the accompanying drawing forming a part of this specification, and in which—

Figure 1 is a view, in perspective, of a portion of a container embodying my invention, and shown partly opened;

Fig. 2 is a longitudinal section of such a container shown on a smaller scale than that of Fig. 1;

Fig. 3 is an end view of the sealed container; and

Fig. 4 is a section taken on line 4—4 in Fig. 2.

Referring more particularly to the drawing, I provide a base 5 of a comparatively stiff substance, such as a sheet of cardboard. On the upper side of base 5 I provide a plurality of spaced partitions 6, and at the ends of base 5 I provide end walls 7. One or more of the partitions 6, as at 8 in Fig. 2, may extend as high as the end walls 7, and be formed similarly thereto. The partition 8 and end walls 7 are preferably formed of rigid construction for the purpose mentioned hereinafter. The partitions 6 and the end walls 7 may be formed in any preferred manner, and a construction which answers my purpose very well is formed of a sheet of paper 9 having folds at spaced intervals therein, forming the partitions 6, and inclosing the partition 8 and end walls 7. In this construction the end walls 7 and partition 8 are pieces of cardboard, but any other suitable substance may be used when so desired. It will then be seen that the paper sheet 9 passes around

the end walls 7 and partition 8, and completely forms the partitions 6.

At one end of the base 5 and its corresponding end wall 7 I secure the end of a string 10, and pass this string longitudinally through the container above the end walls 7, partitions 6 and 8, and extend its end 11 out of the container for the purpose stated hereinafter. Resting on the end walls 7, partition 8 and string 10, I place a comparatively stiff sheet 12. This sheet 12 may be formed of cardboard or stiff paper, and can be of any other suitable substance.

The members already described are enclosed in a sheet or covering 13. This covering is preferably of paraffined paper, but may be of any other suitable substance. One longitudinal edge 14 of the cover is secured to a longitudinal edge at the under side of the base 5 by a suitable agglutinant, and disposed around the parts already mentioned, with its other longitudinal edge 15 also secured to the bottom of the base 5 by a suitable agglutinant. The ends of the covering 13 are folded over, as indicated in Fig. 3, or any other preferred manner, and secured also by an agglutinant. The string 10 is adapted to pass out of the covering as indicated in Fig. 2, so that when it is desired to open the package or container the end 11 of the string is pulled toward the top of the container, tearing a slit as indicated at 16 in Fig. 1. When the string end 11 has reached the under side of cardboard 12, it cannot tear the covering farther in this direction. The string is therefore drawn horizontally from slit 16 across the end of the container under the end of cardboard 12 and along the side of the latter, to sever the covering as indicated in Fig. 1. After tearing or severing the covering at one longitudinal edge of the cardboard 12, the string may be passed back through the severed slit to the other longitudinal edge of the cardboard 13, and sever the covering at such edge, thereby cutting the covering of the package along both longitudinal edges of the cardboard 12, as clearly indicated in Fig. 1. The string 10, is free for lateral swinging around edges of the top sheet 12 substantially as if pivoted at the last point

at which it is secured to the container walls. In the device shown, the string swings about a point where it extends through the end wall 7 at the right hand side of Fig. 2 into the interior of the container. The advantage of providing a package of this sort with partitions as shown coöperating with the string and cardboard 12, is that an article or articles contained in one compartment between an end wall 7 and its next adjacent partition 6 may be removed by tearing the covering, as shown in Fig. 1, without disturbing the contents of the package between the other partitions and end wall. It will therefore be seen that with the use of this container a confection may be placed in each compartment of the container, and by severing the container as indicated above, one or more of the confections, or other similar objects, may be taken from the container without disturbing the other articles therein, and preventing contamination of the articles left in the package or container.

In placing the articles in the container the covering is secured to one side of the base, and the articles placed between the cardboard 12 and base 5, and when the container is full the wrapper or covering is drawn down taut over the cardboard 12, and sealed along its other longitudinal edge to the base. The ends are then sealed in a conventional manner, or as indicated above.

The sheet 12 rests on the top edges of end walls 7 and partition 8, thereby supporting the top of the package above the confections or other articles in the container. This construction has the advantage of supporting a number of packages when in a stack without permitting the weight to rest on the articles in the containers, thereby preserving such articles in their original forms even when a number of the containers are in a stack.

While I have illustrated and described the preferred form of construction of my invention, I do not desire to be limited to the precise details set forth, but desire to avail myself of such variations and changes as come within the scope of the appended claims.

I claim:

1. A container comprising a relatively stiff base; end walls at the ends of the base; a relatively stiff sheet resting on the end walls; a covering inclosing the end walls, base and said sheet; spaced partitions on the base dividing the space between the end walls into a row of small compartments; and a string secured to one end of the container extending through the interior of the latter above said partitions and having its other end protruding from the other end of the container, said string being adapted to

sever the covering at each longitudinal edge of said sheet to open the compartments consecutively.

2. A container comprising a base of relatively stiff material; a covering secured to the edges of the base and inclosing a chamber; spaced parallel vertical walls on the base dividing the chamber into a row of small compartments; a sheet of stiff material resting on certain of said walls under said cover; and a string extending between the sheet of stiff material and the tops of said walls with one end extending from one end of the container and its other end secured inside the other end of the container.

3. A container comprising a base of relatively stiff material; a covering secured to the edges of the base and inclosing a chamber; spaced parallel partitions on the base dividing the chamber into a row of small compartments; end walls of comparatively stiff material at the ends of said base; and a sheet of stiff material resting on said end walls and certain of the partitions under and engaging said cover.

4. A container comprising a base of cardboard; a paper covering secured to the edges of the base and inclosing a chamber; a sheet of paper secured to the upper side of the base and having portions folded and disposed vertically at spaced intervals forming end walls and partitions on the base and dividing the chamber into small compartments; sheets of cardboard in certain of the folded portions of the paper reinforcing said portions; a cardboard sheet disposed on the top edges of the end walls and one of the partitions; and a string extending between the sheet and the tops of the partitions and end walls with one end extending from the container and its other end secured inside of the other end of the container.

5. A container comprising a base and end walls of relatively stiff material; a stiff sheet of substantially the size of said base disposed on the tops of the end walls over said base; a cover inclosing the stiff sheet, end walls and base; and an elongated opening member extending throughout the length of said stiff sheet under the latter with one end secured to one of the members inside of said cover forming a pivotal point about which the opening member is adapted to swing to sever the cover and its other end extending out through a portion of said cover.

6. A container comprising a frame of relatively stiff material comprising a base with end walls at the ends of said base and a top sheet having its ends disposed on the upper edges of the end walls; a covering inclosing the base, end walls and top sheet; a string secured to one end wall, extending

under the top sheet and between one end of the latter and the upper edge of one end wall with one end portion extending from the covering, said string being adapted to move pivotally about its connection with said end wall along the under sides of the edges of the top sheet just above articles in the device to sever the covering.

In testimony whereof I have signed my name to this specification, in the presence 10 of two subscribing witnesses, on this 18th day of November, A. D. 1915.

JOSEPH RICE.
